UNITED STATES PATENT OFFICE.

MARY JOHNSON, OF NEW YORK, N. Y.

HAND-PROTECTOR.

1,215,163.

Specification of Letters Patent.

Patented Feb. 6, 1917.

Application filed April 12, 1916. Serial No. 90,595.

To all whom it may concern:

Be it known that I, MARY JOHNSON, a citizen of the United States, and a resident of the city of New York, borough of Manhattan, in the county and State of New York, have invented a new and Improved Hand-Protector, of which the following is a full, clear, and exact description.

The invention relates to laundry appliances and its object is to provide a new and improved hand protector or mitten arranged to enable the user to evenly and thoroughly rub hot starch into cuffs, collars and similar articles while in process of manufacture and without danger of injury to the hand of the operator.

In order to accomplish the desired result, use is made of a hand protector in the form of a mitten made of a textile fabric and provided at the inside with a pad overlying the under side of the finger and palm portions, and formed of a plurality of layers of textile materials with the edges attached to the edges of the mitten. Use is also made of extending the palm in an outward direction to form closing flaps adapted to pass onto the back of the hand and to overlap thereon, and fastening devices on the said flaps for fastening the flaps together at the back of the hand.

A practical embodiment of the invention is represented in the accompanying drawings forming a part of this specification, in which similar characters of reference indicate corresponding parts in all the views.

Figure 1 is a perspective view of the hand protector as applied and showing the finger portion in use for rubbing starch onto a cuff;

Fig. 2 is a similar view of the same and showing the palm in use for applying starch to a cuff;

Fig. 3 is an enlarged inverted plan view of the hand protector with parts broken out; and

Fig. 4 is a sectional side elevation of the same on the line 4—4 of Fig. 3.

In the manufacture of stiff bosom shirts, cuffs, collars and similar articles, it is necessary to rub hot starch into the textile material for stiffening purposes. This application of the starch is mostly done by hand and even with the use of machines constructed for this purpose it frequently becomes

necessary to finish the rubbing in of the starch by hand. The rubbing in of the starch by hand is very hard on the hand of the operator as both the fingers and the palm have to be used and the hand soon becomes raw from the effect of the hot starch and the contact with the weave of the material. Mittens or gloves of leather or other similar material cannot be effectively used as they are not sufficiently flexible to insure a thorough and even rubbing in of the starch. In order to protect the operator's hands and to allow a proper rubbing in of the hot starch into the fabric material is the main object of the invention presently described in detail.

The hand protector is formed of a top 10 and a mitten bottom 11, the top and bottom being overlapped and fastened together along the edges by stitches 12, and the rear edges of the top and bottom 10 and 11 are doubled up, and each doubled-up portion is provided with rows of stitches 13 and 14 to form binding edges, at the same time providing an opening for the introduction of the hand. Within the hand protector thus formed is arranged a pad 15 overlying the under side of the finger and bottom portions and formed of a plurality of layers of textile materials, the edges of the pad 15 being attached by the stitches 12 to the edges of the top 10 and the bottom 11. The rear edge of the pad 15 is fastened by the stitches 14 in position to the bottom 11. In practice the parts 10 and 11 are preferably made of muslin while the layers forming the pad 15 have the lowermost layer muslin while the remaining layers are preferably made of gauze, as indicated in Fig. 3.

The palm of the hand protector is provided with sidewise extensions forming flaps 16 and 17 adapted to be passed onto the back of the wearer's hand with the ends of the flaps overlapping at the back of the hand. The ends of the flaps 16 and 17 are provided with fastening devices 18 and 19, such as socket and stud members, adapted to engage one the other to fasten the flaps in overlapping position together. By the arrangement described the palm of the hand protector remains completely unobstructed for applying and rubbing purposes.

When the hand protector is in position on the hand of the operator then the pad bot-

tom finger portion can be readily passed into the receptacle containing the hot starch to take up a sufficient quantity of this starch and rub it into the cuff, collar or other article to be starched. If necessary, a further rubbing action may be given by raising the fingers and with them this portion of the protector to allow the use of the palm for a further rubbing action of another nature.

It will be noticed that as the bottom 11 and the pad 15 are both of light textile fabric the starch can be readily taken up, applied to the article to be starched, and evenly and thoroughly rubbed into the same without injury to the hand of the operator. It will further be noticed that by the construction described a desired pliability is had of the bottom 11 and the pad 15 so that the operator can deftly apply the starch taken up to every part of the article to be starched, and at the same time the hand of the operator is protected.

The protector shown and described can be cheaply manufactured so that when it becomes torn by repeated use it can be readily thrown away and a new one used.

Having thus described my invention, I

claim as new and desire to secure by Letters Patent:—

1. As an article of manufacture, a hand protector in the form of a mitten made of a textile fabric and provided at the inside with a pad overlying the under side of the finger and palm portions and formed of a plurality of superimposed layers of textile materials with the edges attached to the edges of the mitten, the bottom layer of the pad being of the same material as the mitten and the remaining layers being of a lighter material than the said bottom layer.

2. As an article of manufacture, a hand protector in the form of a mitten made of a textile fabric and provided at the inside with a pad overlying the under side of the finger and palm portions and formed of a plurality of superimposed layers of textile materials with the edges attached to the edges of the mitten, the palm having its sides extended in an outward direction to form closing flaps adapted to pass onto the back of the hand and to overlap thereon, and fastening devices on the said flaps for fastening the flaps together at the back of the hand.

MARY JOHNSON.
